(57) **CLAIM**

The ornamental design for a tablet display screen with graphical user interface, as shown and described.

DESCRIPTION

FIG. 1 is a front view of the first image in a sequence for a tablet display screen with graphical user interface, showing my new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the seventh image thereof;

FIG. 8 is a front view of the eighth image thereof;

FIG. 9 is a front view of the ninth image thereof;

FIG. 10 is a front view of the tenth image thereof;

FIG. 11 is a front view of the eleventh image thereof;

FIG. 12 is a front view of the twelfth image thereof;

FIG. 13 is a front view of the thirteenth thereof;

FIG. 14 is a front view of the fourteenth image thereof;

FIG. 15 is a front view of the fifteenth image thereof;

FIG. 16 is a front view of the sixteenth image thereof;

FIG. 17 is a front view of the seventeenth image thereof;

FIG. 18 is a front view of the eighteenth image thereof; and,

FIG. 19 is a front view of the nineteenth image thereof.

The broken line showing the display screen illustrates the portions of the article that form no part of the claimed design.

The appearance of the figures sequentially transitions between FIGS. 1-19. The process or period in which one image transitions to another forms no part of the claimed design.
